UNITED STATES PATENT OFFICE.

DALE R. BARD, OF BRYAN, OHIO.

FASTENER FOR ROOFING SHEETS.

Application filed March 31, 1928. Serial No 266,139.

This invention relates to sheet metal fasteners for securing prepared roofing sheets in place, but more particularly to nailing strips of the type having a series of cleats or fasteners integrally joined together.

An object of this invention is to provide a simple and efficient fastener for roofing sheets which will not tear the sheets when wind blows under the sheets and causes flapping thereof, but permits flapping movement of the sheets relative to the fasteners without affecting the seal or damaging the sheets. Other objects will hereinafter appear.

An illustrated embodiment of the invention is shown in the accompanying drawings, in which:

Fig. 1 is a top plan view of the nailing strip showing the manner in which it is applied;

Fig. 2 is a perspective view of one of the fasteners;

Fig. 3 is a diagrammatic view to show the curvature of the nail receiving portion; and

Fig. 4 is a transverse section through the nail receiving portion of one of the fasteners in Fig. 1.

The illustrated embodiment of the invention comprises a pair of roofing sheets 1, which are separated at their adjacent edges in the usual manner as applied for roofing purposes, leaving a space 2 between contiguous sheets. In order to seal this space, a nail-receiving strip 3 spans the space and provides a weather resistant seal. Each strip 3 may be of about 30 inches in length, and is made of relatively light gage sheet metal, being composed of a plurality of individual cleats or fasteners 4 integrally connected to each other.

The strip 3 is secured in place by nails 5 extending through holes in individual fasteners 4. Each fastener is provided with a raised nail-receiving portion 6, thereby providing a concavo-convex form. The nail-receiving portion 6 converges from opposite ends towards the central part, and is symmetrically curved in the manner shown.

As diagrammatically indicated in Fig. 3, a line 7, drawn tangent to the center of the nail-receiving portion, forms with a chord 8 from the center of the nail-receiving portion to either end thereof, an angle of the order of

12°. By virtue of this construction, the nail-receiving portion is spaced but a slight distance away from the surface to which it is attached, but the elevation is sufficient so that when force is applied by driving a nail into place, all edges thereof are forced into intimate sealing engagement with the engaging surface.

Depending from opposite sides of the nail-receiving portion 6 are vertically disposed, outwardly inclined sides 9. The sides 9 form, with the adjacent edge of the nail-receiving portion, a sector, thereby providing a construction which, when the upper surface of the nail-receiving portion is struck by a hammer or other tool, the sides are forced inclinedly downward into the roofing material, and at the same time the ends are forced into intimate engagement with the material engaged.

A cardinal feature of this invention consists in providing upturned longitudinal edges 10 at each side of the cleat forming a continuous flange on opposite sides of the nailing strip. The one advantage of the flanges 10 is that when the cleat or strip is in place, liability of tearing or severing the roofing material is prevented.

In case of partially worn sheets permitting the wind to get under the same and flap them, it is found that the ordinary nailing strips are not satisfactory, because of the sharp side edges acting as knives to sever the flapping sheets along the line of connection.

By my construction it is apparent that the liability of tearing of the sheets is eliminated, as the sharp edges at the side of the strip are eliminated, and a curved edge is provided.

While I have provided a construction which satisfies the objects primarily stated, it is to be understood that numerous changes in details of construction and arrangement may be effected without departing from the spirit of the invention as defined in the following claim, and the above description is to be considered by way of illustration and not of limitation.

What I claim as new and desire to secure by Letters Patent is:

A sheet metal fastener having a rectangular

base, flat longitudinal and symmetrically curved nail-receiving portion, the curvature from opposite ends being such that a line tangent to the center thereof forms with a 5 chord from such center to either end an angle of the order of 12° , said nail-receiving portion diverging uniformly in opposite directions

from the central part thereof, and sides depending downwardly and outwardly from said nail-receiving portion, and upturned flanges on the side edges thereof. 10

In testimony whereof I have hereunto signed my name to this specification.

DALE R. BARD.
